TILE ARCH STRUCTURE

Filed Nov. 12, 1948

UNITED STATES PATENT OFFICE

2,600,460

TILE ARCH STRUCTURE

Philip W. Antill, Ridgefield Park, N. J., assignor
to M. H. Detrick Company, Chicago, Ill., a cor-
poration of Delaware

Application November 12, 1948, Serial No. 59,714

4 Claims. (Cl. 110—99)

1

This invention relates to arch structures for industrial furnaces, particularly open hearth furnaces, in which the refractory materials are subjected to intense heat above the melting temperatures of steel, and it is among the objects thereof to provide a tile structure for furnace roofs in which the ends of the roof employ skew-back castings for retaining standard shape tile as distinguished from special shape skew-back structures requiring special refractory shapes.

It is a further object of the invention to provide an arch construction in which the end tile cooperate with the walls of the furnace in a manner to eliminate the burning out of the tile as frequently occurs in conventional construction.

It is still a further object of the invention to provide an arch structure of skew-back retaining means and tile which may be sprung to permit expansion and contraction of the tile.

These and other objects of the invention will become more apparent from a consideration of the accompanying drawing, constituting a part hereof, in which like reference characters designate like parts, and in which

Fig. 1 is a vertical cross-sectional view, partially in elevation, of a portion of an open hearth furnace embodying the principles of this invention; and

Fig. 2 is a similar view taken at right angles to the view of Fig. 1.

In the drawing the numeral 1 generally designates the roof of an open hearth furnace consisting of tapered tile 2 which are suspended by hangers 3 from curved rods 4 that in turn are suspended by links 5 from I-beams 6 mounted transversely of I-beams 7 that are supported on the buckstays 8 disposed around the outside of the furnace, links 5 being resiliently mounted by springs 9 as shown in Fig. 2. The arch construction is such that it may expand and contract with temperature conditions in the furnace without separation of the tile, which is well known in the art and constitutes no part of the present invention.

Because of the difference in temperature of the inner wall 10 of the arch, which is exposed to the intense heat of the furnace, and the colder outer wall 11 of the arch, there is a tendency for the ends of the arch to move on the upright walls 8 and the amount of expansion or contraction would be greater on the bottom of the arch tile 2 than at the top thereof.

In conventional practice special shaped skew-back tile has been employed on the ends of the arch, which requires stocking of a large number

2

of different shaped refractory pieces for replacement purposes. In accordance with the present invention, such special forms of refractory are eliminated and standard refractory brick 12 and 13 may be employed by utilizing a special shaped skew-back casting 14 which is of zigzag form, as shown in Fig. 1 of the drawing.

By virtue of the zigzag shape of the skew-back, the end refractory brick 13 projects beyond the lower face 10 of the arch into a sand seal which may be ganister, such as chrome ore or the like, designated by the reference character 15. This construction prevents the products of combustion from passing through the wall and seals off the arch while permitting relative movement of the arch tile to the wall, the sand seal being such as to prevent a straight line passage of the products through the seal of the wall, and the end brick 13 extending into the sand seal prevents burning out of the skew-back casting 14.

The skew-back casting may be yieldingly restrained against movement by a lever 16 pivotally mounted at 17 and biased by a spring 18, the end of the lever 16 being shaped complementary to the zigzag shape of the skew-back 14 for effecting abutting engagement therewith over a relatively large area. The lever 16 may be adjusted by providing perforations 19 as shown.

Other features of the furnace need not be described as the present invention deals primarily with the special shaped skew-back which permits the use of standard refractory brick in furnace arch structures, that provides a shiplap seal and protects the skew-back casting from the intense heat of the furnace.

Although one embodiment of the invention has been herein illustrated and described, it will be evident to those skilled in the art that various modifications may be made in the details of construction without departing from the principles herein set forth.

I claim:

1. In a tile arch structure for industrial heating furnaces, a skew-back roof tile support comprising a plate of zigzag shape in cross section in a vertical plane diametrically through the arch having the upper face thereof abutting the end tile of the arch and having the bottom face supported independently of the arch, and refractory brick disposed intermediate the upper and bottom end faces of the skew-back to constitute a refractory lining for the skew-back plate.
2. In an industrial heating furnace having a tile arch roof, a skew-back roof tile support comprising a plate of zigzag shape in cross section in

a vertical plane diametrically through the arch having a face thereof abutting the end tile of the arch and having the bottom face supported on a wall of the furnace, and refractory brick disposed intermediate the upper and bottom end faces of the skew-back in the zigzag faces thereof to constitute refractory surfaces intermediate the furnace chamber and the skew-back plate, one of said refractory brick extending downward beneath the lower face of the arch and skew-back to constitute a sealing means between the arch and supporting wall.

3. In an industrial heating furnace, a roof comprising a plurality of tapered tile with their faces abutting to constitute a continuous arch, a skew-back plate supporting the ends of the arch of zigzag shape in cross section in a vertical plane diametrically through the arch with the upper face of the plate abutting the end tile of the arch and the bottom face resting on a wall of the furnace, and refractory brick disposed in the zigzag shoulders of the skew-back abutting the shoulders and off-set faces thereof on the side of the furnace chamber, said brick constituting a continuation of the arch.

4. The combination with a furnace wall of a refractory arch supported thereon, said wall hav-

ing a recess for receiving ganister, means for yieldingly supporting the end of the arch on said wall comprising a skew-back casting of zigzag shape in cross section in a vertical plane diametrically through the arch having the bottom face resting on the wall and having its upper face engaging the end face of the arch tile, refractory brick disposed between the end tile of the arch and the skew-back in the recesses formed by the zigzag shape to constitute an extension of the arch, one of said brick extending downward into the recess of the wall to constitute a seal with the ganister disposed between the wall and arch.
